CLAIM

The ornamental design for a stent with commissure attachments, as shown and described.

DESCRIPTION

FIG. 1 is a top perspective view of the stent with commissure attachments showing our design;

FIG. 2 is a front side elevational view thereof;

FIG. 3 is a rear side elevational view thereof;

FIG. 4 is a right side elevational view thereof, the left side elevational view being a mirror image of the right side; and, FIG. 5 is an enlarged front elevational view of a portion of the stent with commissure attachments shown in FIG. 2.

It is noted that any broken line illustration of environmental structure in the drawing is not part of the claimed design.

1 Claim, 5 Drawing Sheets
